US00D960374S

(12) **United States Design Patent** (10) Patent No.: **US D960,374 S**
(45) Date of Patent: **** Aug. 9, 2022**

(54) **HANDLE FOR AN ULTRASONIC DIAGNOSIS APPARATUS**

(71) Applicant: **CANON MEDICAL SYSTEMS CORPORATION**, Otawara (JP)

(72) Inventor: **Sakiko Tanimoto**, Tokyo (JP)

(73) Assignee: **Canon Medical Systems Corporation**, Otawara (JP)

(**) Term: **15 Years**

(21) Appl. No.: **29/748,750**

(22) Filed: **Sep. 1, 2020**

(30) **Foreign Application Priority Data**

May 15, 2020 (JP) 2020-009601

(51) LOC (13) Cl. **24-01**

(52) U.S. Cl.

USPC **D24/186**; D24/185; D34/27

(57) **CLAIM**

The ornamental design for a handle for an ultrasonic diagnosis apparatus, as shown and described.

DESCRIPTION

FIG. 1 is a perspective view of a handle for an ultrasonic diagnosis apparatus showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right-side elevational view thereof; and,

FIG. 8 is a reference view showing the article in use thereof. The broken lines represent environmental subject matter and form no part of the claimed design.
